CUPOLA FURNACE

Francis J. Zippler, Pittsburgh, Pa., assignor of
one-fifth to Ralph W. Carson, Pittsburgh, Pa.

Application January 3, 1940, Serial No. 312,274

4 Claims. (Cl. 266—30)

This invention relates to furnaces and more particularly to cupola furnaces.

The primary object of this invention is the provision of a twyer construction of the furnace which may be readily adjusted for varying paths of air entering the furnace and acting to pre-heat to prevent metal freezing, the twyer construction including removable twyer blocks readily adjustable relative to each other for controlling the paths of air into the furnace and which may be readily removed when damaged without disturbing the cupola or other parts of the furnace and which also permits easy removal of the bosh blocks of the cupola and adjustments and replacements may be rapidly accomplished thereby preventing undue delay in the operation of the furnace or the closing down of the furnace operation for periods of time expensive to production.

With these and other objects in view, this invention consists in certain novel features of construction, combination and arrangement of parts to be hereinafter more fully described and claimed.

For a complete understanding of my invention, reference is to be had to the following description and accompanying drawings, in which

Figure 1 is a fragmentary vertical sectional view illustrating a portion of a cupola furnace equipped with a twyer construction constructed in accordance with this invention.

Figure 1^a is a perspective view illustrating one of the twyer blocks.

Figure 2 is a fragmentary vertical sectional view showing a modification of the twyer construction.

Figure 3 is a fragmentary vertical sectional view showing another modification of the twyer construction.

Figure 3^a is a perspective view illustrating one of the blocks shown in the form of twyer construction disclosed in Figure 3.

Figure 4 is a fragmentary vertical sectional view illustrating another modification of twyer construction.

Figure 4^a is a perspective view illustrating one of the twyer blocks of the form of twyer construction disclosed in Figure 4.

Figure 5 is a fragmentary vertical sectional view illustrating another modification of twyer construction.

Figure 5^a is a perspective view illustrating one of the blocks employed in the form of twyer construction shown in Figure 5.

Figure 6 is a vertical sectional view of a further modification in my twyer construction.

Figure 7 is a view taken along the line 7—7 of Figure 1.

Figure 8 is view taken along the line 8—8 of Figure 1.

Referring in detail to the drawings, a fragmentary portion of the furnace is indicated by the character 1 and includes a neck portion 2, a throat portion 3 and a metal receiving chamber 4. The construction of cupola furnace of this type is well known in the art and it is not thought necessary to further describe in detail the construction of the furnace itself. Formed in the walls of the furnace construction is an air chamber 5 fed in any well known manner by air under pressure. This also is well known in cupola type furnaces.

Arranged in annular formation within the throat portion of the furnace are bosh blocks 6

each including an upwardly and inwardly inclined portion 7 and a vertical portion 8. Formed on the bosh block whereby the portions 7 and 8 merge together is a hook-shaped flange 9 to engage or interlock with an upstanding flange 10 formed on an upper supporting plate 11. An intermediate supporting plate 12 is arranged below and spaced from the upper supporting plate. Hook shaped portions 13 and 14 are formed on the plates 11 and 12 and interlock with upstanding flanges 15 and 16 formed on a supporting block 17, the latter having an opening 18 for the purpose of receiving a bolt or like fastener for securing the supporting block on the usual shell (not shown) of the furnace construction. It is

to be understood that the supporting block 17 and supporting plates 11 and 12 are arranged in the air chamber 5. The vertical wall 8 of the bosh block engages with and depends below the supporting plate 11 so as to cooperate with the hook shaped portion 9 in removably securing the bosh block on the supporting plate 11. To remove the bosh block it is only necessary to elevate the same a limited distance in order that the hook shaped portion 9 clear the flange 10.

The intermediate supporting plate 12 includes an outwardly and downwardly inclined wall 19 cooperating with a wall 20 in forming a space to removably receive twyer blocks 21 each of a construction as shown in Figure 1^a. The twyer blocks when assembled in the furnace may be spaced at selected distances apart to form therebetween air passages communicating the air chamber with the throat portion in which air will enter the throat portion horizontally thereof. Each twyer block 21 has a cutout portion 22 and

one end of said twyer block is enlarged to form a depending portion 23, a wall of which aligns with one of the walls of the cutout portion 22 for the purpose of deflecting air from the chamber 5 downwardly and inwardly of the throat portion of the furnace. The walls 19 and 20 contacting the block 21 complete within the block the air passage 24 including an upwardly and inwardly inclined run and a downwardly and inwardly inclined run so that the air passing through the passage will be preheated. Also it is to be understood that the air passing between the twyer blocks will be preheated and thereby prevent freezing of the metal in the metal receiving chamber.

A lower supporting plate is indicated by the character 26 which may be sectional and is secured on the shell (not shown) of the furnace. The lower supporting plate 26 includes sections 27 and 28 detachably connected, as shown at 29, that is, the section 27 is bifurcated to receive a portion of the section 28. The other portion of the section 28 inclines upwardly and inwardly with respect to the furnace and forms a support for the wall 20, the latter having a notched portion 30 to receive the upper edge of the section 28 of the lower supporting plate 26. The wall 20 includes angularly related portions, as clearly shown in Figure 1, which portions cooperate with the block in forming the air passage 24 of the shape described.

The twyer blocks 21 supported by the construction described will permit the twyer blocks to be readily adjusted in a circumferential path for varying the distance between said blocks and thereby permit the air passages defined by said blocks to be varied in size, that is, the air passages which admit air into the furnace in upward and inward paths. Also, the blocks being adjustable relative to each other will bring about the adjustment of the paths of air which enter the throat of the furnace in a downward and inward direction relative to each other. The twyer blocks being easily removable will permit them to be replaced by others when damaged within a comparatively short period of time and also due to the twyer construction the bosh blocks may be readily replaced by others when damaged within a comparatively short period of time. The mounting of the supporting plates within the air chamber 5 also permits these plates to be removed and replaced by others when damaged and also the walls 19 and 20 may be easily removed and replaced by others when damaged.

Referring to my modified form of twyer construction as shown in Figure 2, the bosh blocks 31 and twyer blocks 32 are similarly constructed to the bosh blocks and twyer blocks described in connection with the disclosure made in Figure 1. In the modification shown in Figure 2 the intermediate supporting plate 12 is eliminated and the upper supporting plate 33 thereof carries the downwardly and outwardly inclined wall 34 similar in construction to the wall 19 and which cooperates with a wall 35 similar in construction to the wall 20 in removably supporting the twyer blocks 32. The lower supporting plate 36 supports the wall 35, the latter being removable therefrom. The lower supporting plate 36 in this instance does not include the separable sections. Arranged between the upper and lower supporting plates are supporting elements 37 each of substantially I beam construction and when assembled in the air chamber 5 are spaced apart so as not to unduly interfere with the flow of

air in the air chamber. The supporting elements 37 have flanges 38 acting as supports for the outer ends of the walls 19. In the construction described in Figure 2 paths of air will enter the throat portion of the furnace in an upward and inward direction and also downwardly and inwardly thereof. Further, the construction described in Figure 2 permits easy removal and replacement of the twyer blocks and bosh blocks as well as permitting the twyer blocks to be adjusted relative to each other for varying the distances between said blocks.

Referring to my modified form of invention as shown in Figure 3, upper and lower supporting plates 39 and 40 are employed, the lower supporting plate 40 being similar in construction to the lower plate 36 except the inner end thereof has a gradual curve thereto, as indicated at 41, to form a rest for the twyer blocks 42. The upper supporting plate 39 supports the bosh blocks 42' in a manner similar to the supporting of the bosh blocks 31 and 6. A depending wall 43 is formed on the plate 39 and cooperates with the lower plate 40 in supporting the twyer blocks 42. In this instance the twyer construction includes a series of upper and lower supporting plates so that the depending walls 43 will be spaced from each other and permit air of the air chamber to pass therebetween and also between the twyer blocks entering the throat portion of the furnace in upward and inward directions or in an upward and inward path.

Each twyer block 42 has formed therein an upwardly and inwardly extending passage 44 for the purpose of directing air from the chamber 5 upward and inwardly of the throat portion of the furnace. The bosh blocks 42' and twyer blocks 42 can be quickly removed and replaced when necessary and the twyer blocks 42 can be easily adjusted relative to each other for the purpose of varying the spaces therebetween.

Referring to the modification of my invention shown in Figures 4 and 4^a, the upper and lower supporting plates 46 and 47 are similar in construction to the supporting plates 39 and 40. However, the supporting plates 46 have integral therewith downwardly and outwardly inclined walls 48 each offset, as shown at 49. The walls 48 and lower supporting plate cooperate in removably supporting twyer blocks 50. One face of each block 50 is shaped to match the wall 48 and one face has formed thereon a rib 51 to engage with the rest provided on the lower supporting plate 47. Each twyer block 50 has a cut-away portion to form an air passage 52 for admitting air horizontally into the throat portion of the furnace from the air chamber. The spaces formed between the blocks 50 will admit air in paths extending from the air chamber upwardly and inwardly to the throat portion of the furnace.

Referring to the modification shown in Figures 5 and 5^a upper and lower supporting plates 53 and 54 are employed, the upper plates 53 being supported by blocks 55 secured on the shell (not shown) of the furnace and said upper plates removably support bosh blocks 56 which in this instance each includes a downwardly and outwardly inclined wall 57 entering the air chamber above the lower plates 54. Received between the walls 57 of the bosh blocks and the lower supporting plates 54 are twyer blocks 58 of solid formation and each of substantially triangular shape in cross section. These blocks are spaced from each other and cooperate with the walls

51 in forming air passages which will direct air from the air chamber upwardly and inwardly with respect to the throat portion of the furnace.

Figure 6 illustrates a further modification, in which the bosh blocks 60 are provided with flanges 61 for hooked engagement with a flange 62 fashioned on a plate 63, which plate is provided with a downwardly and outwardly inclined wall 64. A plate 65 is mounted on the brick bed 66 and includes a right-angular wall 67 connected with an angular wall 68 paralleling the inner face of the wall 64, and the wall 68 is connected with a downwardly and inwardly inclined wall 69.

Figure 6 illustrates a tuyere block 70 as having a wedge-like extension 71 having its face 72 positioned adjacent the inner face of the wall 64, and the tuyere block includes a shoulder 73 resting on the ledge 74 of the plate 65. The block also includes a shoulder 75 which engages the plate 63, and the block includes a second wedge element 76 fitting the angular wall 69, with the edge 77 of the block terminating flush with the brick wall face 78.

Between the plates 63 and 65 I position supporting brackets 79, which are substantially U-shaped when viewed according to Figure 6 and located in the air chamber 80, but spaced apart so as not to impede the flow of air into the chamber.

The brick wall 81 above the plate 63 is materially thicker than the wall 78 to provide a constricted neck 82, and the wall above the neck has an upwardly and outwardly inclined bosh face 83 running into the straight wall face 84. Within the wall 81 I incorporate a plurality of upper tuyeres 85, 86 and 87, which tuyeres are respectively flanged at 88 for bolted connection with the cupola shell 89. Tuyeres 85, 86 and 87 are spaced vertically and a plurality of each tuyere may be radially distributed circumferentially of the neck 82. Each tuyere is downwardly inclined in a small degree and is of hollow formation and arranged in registration with a port 90 in the shell 89. To the shell 89 I secure conically shaped flanges 91 constituting seats for plungers or valves 92, 93 and 94 respectively associated with the tuyeres 85, 86 and 87. Valves 92, 93 and 94 include conically shaped heads 95 arranged to have seating engagement with the flanges 91, and each head is connected with a hollow rod 96 slidable in a tubular member 97 extending through an opening 98 in a wind box 99. The tubular members have flanges 100 engaging the wall of the wind box 99 to be bolted thereto.

Heads 95 are bored at 101, which bores are of the same diameters as the bores in the hollow rods 96 with the common bores providing peep holes to enable the attendant to make visual observations from time to time. Each rod is provided with an actuating handle 102, and the ports 90 leading into the tuyeres 85, 86 and 87 may be completely closed by pushing their respective valves 92, 93 or 94 into the flanges 91. Obviously, the amount of air flowing through the ports may be modified in different degrees through adjustment of the valves.

Figure 6 illustrates the wind box 99 as being provided with a blast tube 103 having a neck 104 bolted to the shell 89 and communicating with the air chamber 80. A damper 105 is rotatably journaled in the blast pipe 103 and includes an actuating member 106 which permits the damper to be adjusted to different positions for varying the volume of air passing into the chamber 80.

5 Wind box 99 is provided with an air blast pipe 107. Neck 104 is provided with a port 108 and a peep hole device 109, and the neck is also provided with a removable plug 110 which may be removed to permit molten iron to flow to the floor in case of an overflow in the tuyere.

Wall 64 and the wall 68 are angled in such manner as to direct the flow of air upwardly and inwardly of the furnace, and the tuyere blocks 70 may be spaced at desirable intervals. In addition, the wall 69 is so angled as to permit the air blast to be directed downwardly inside the furnace, in addition to preventing molten iron from dropping into the tuyere space. The controlled tuyeres 85, 86 and 87 permit effective control of the air blast in the main upper tuyere region.

20 In use, a cupola furnace of a well known type may be readily equipped with a tuyere construction as heretofore described and if desired the furnace may employ at one time tuyere blocks all of one construction and in accordance with any one of the forms heretofore described or the furnace may be equipped at one time with tuyere blocks differing in construction and in accordance with that described in connection with various forms shown in the drawings.

25 When a furnace is equipped at one time with the different forms of tuyere blocks and supports therefor as has been described in this application it is possible to obtain various directions of flow of air into the furnace from the air chamber some of which may blow or pass straight in horizontally while other air may be directed downwardly in the furnace and still other air may be directed upwardly into the furnace. Air blowing downwardly into the furnace converts the well of the cupola into a preheating zone and the molten iron or metal coming from this zone 30 retains a high temperature longer than iron coming from the usual type of well. The tuyere constructions shown and described in this application when employed will permit a large saving in repair cost with greater melting speed of the 35 metal with a less consumption of fuel.

40 Having thus described certain embodiments of my invention in detail, it is, of course, understood that I do not desire to limit the scope thereof to the exact details set forth except insofar as those details may be defined in the appended claims.

45 What is claimed is:

1. In a furnace construction having a throat portion above a metal receiving chamber and an air chamber adapted to receive air from a source, a supporting member extending horizontally about said throat adjacent said air chamber, bosh blocks mounted on said supporting member, vertically spaced upper and lower walls extending horizontally about said throat inside said air chamber, tuyere blocks positioned between said upper and lower walls, said tuyere blocks having vertical walls engaging said upper and lower walls to provide air passages, and air deflecting means on said tuyere blocks arranged to deflect air upwardly and then downwardly and inwardly of said throat portion.

2. In a furnace construction having a throat portion above a metal receiving chamber and an air chamber adapted to receive air from a source, vertically spaced upper and lower walls extending horizontally about said throat inside said air chamber, said upper and lower walls inclining upwardly, and tuyere blocks fitting between said upper and lower walls, said tuyere blocks being

spaced one from the other and coating with said upper and lower walls to provide air passages, said tuyère blocks being adjustable toward and away from each other to vary the size of said air passages.

3. In a furnace construction having a throat portion above a metal receiving chamber and an air chamber adapted to receive air from a source, removable tuyère blocks, means within the air chamber, for supporting said tuyère blocks, said means and said tuyère blocks being fashioned to provide air passages adapted to deliver air upwardly, downwardly and inwardly of said throat portion, and bosh blocks supported by the supporting means and engaging the upper faces 15 of the tuyère blocks.

4. In a furnace construction having a throat

portion above a metal receiving chamber and an air chamber adapted to receive air from a source, a supporting member extending horizontally about said throat adjacent said air chamber,

5 bosh blocks having hooked portions mounted on said supporting member, vertically spaced upper and lower walls extending horizontally about said throat inside said air chamber, tuyère blocks positioned between said upper and lower walls and engaging the lower ends of the bosh blocks, said tuyère blocks having vertical walls engaging said upper and lower walls to provide air passages, and air deflecting means on said tuyère block arranged to deflect air upwardly and then downwardly and inwardly of said throat portion.

FRANCIS J. ZIPPLER.
